UNITED STATES PATENT OFFICE.

HENRY C. BRAUN AND ARTHUR FORD-LLOYD, OF LONDON, ENGLAND.

DESIGN FOR A CASE FOR ELECTRO-MEDICAL BATTERIES.

SPECIFICATION forming part of Design No. 20,207, dated October 14, 1890.

Application filed April 21, 1890. Serial No. 348,984. Term of patent 3½ years. Registered in England May 8, 1888, No. 7,083, and in France June 26, 1889, No. 195,639.

To all whom it may concern:

Be it known that we, HENRY CHARLES BRAUN and ARTHUR FORD-LLOYD, subjects of the Queen of Great Britain, and residents of London, in the county of Middlesex, England, have invented and produced a new and original Design for the Front of a Case or Box for an Electro-Medical Battery, (registered in Great Britain May 8, 1888, No. 7,083, and in France June 26, 1889, No. 195,639,) of which the following is a full, clear, and exact specification.

The figure represents a front view, in perspective, of a case for an electro-medical battery, which fully illustrates our design.

A is the top, B the bottom, and CC round columns or pillars supported by B. The top piece of the box or casing is raised to a point in the center and slopes toward each side.

The leading features in our design consist **20** in the sloping top A and round pillars or columns CC.

What we claim is—

The design for the case for an electro-medical battery, as herein shown and described, **25** consisting of the front, which comprises top A, bottom B, and round pillars or columns CC, as set forth.

In testimony that we claim the foregoing we have hereunto set our hands this 25th day **30** of May, 1889.

HENRY C. BRAUN.
ARTHUR FORD-LLOYD.

Witnesses:

JAMES FLEMING,
A. STEAD.
